ARTIFICIAL FLOWER-MAKING DEVICE

Robert N. Burton, River Forest, Ill., assignor to
Kirchen Bros. Inc., Chicago, Ill., a corporation
of Illinois

Application October 20, 1934, Serial No. 749,141

4 Claims.

(Cl. 41—2)

This invention relates to devices for making artificial flowers. Its object is to provide such means in a form which is extremely simple to produce and economical to manufacture, and which shall occupy no unnecessary space in the package in which the outfit is marketed. It consists of certain features and elements of construction in combination and in the method of using the same, as herein shown and described and as indicated by the claims.

In the drawing:

Figure 1 is a perspective view showing the parts of the device in a diagrammatic arrangement with petal units to be employed in making the flower. Figure 2 is a vertical section showing the parts in assembled relation in the process of making the flower.

Figure 3 is a perspective view showing the assembled parts in inverted position for applying the stem wire to the calyx.

Figure 4 is a perspective view of a flower made in accordance with this invention.

Figure 5 is a perspective view similar to Figure 1 showing a modified apparatus.

Figure 6 is a sectional view similar to Figure 2 showing the parts of said modified apparatus in their relative positions during the formation of a flower.

Figure 7 is a perspective view illustrating the position of the modified apparatus for attaching the stem wire.

Figure 8 is a perspective view similar to Figure 1 but showing a further modification of the apparatus.

The paper flowers made in accordance with this invention are usually composed of a plurality of petal units, each unit being in the form of a disk of thin tissue paper or wood fiber tissue, or similar material with its edge suitably scalloped or fringed to produce the effect of a plurality of petals. These units are arranged in super-imposed relation to each other and their centers are then offset and gathered into the form of a calyx, resulting in a relatively informal and natural gathering and shaping of the peripheral portions of the petal units into some such arrangement as indicated in Figure 4.

For the convenient handling and shaping of the parts I provide a simple apparatus which, as shown in Figure 1, consists of a standard pasteboard box, 1, having side walls or flanges, 1^a, a cover, 2, with lateral flanges, 2^a, and, in addition, a wooden stick or plunger, 3. Since the petal units are approximately circular in form, the box is preferably square in plan view, and the only

special feature of construction required to convert it to my special purpose is the formation of a circular aperture, 4, in the bottom of the box, and a circular aperture, 5, centered in the cover. Preferably, one of these apertures is slightly larger than the other, and, as shown, the aperture, 4, in the box itself is the smaller.

To form a flower the box, 1, is inverted on a table or other suitable support and one of the petal units, A, is centered thereon over the aperture, 4, as indicated in dotted outline. The box cover, 2, is then inverted and placed upon the petal unit, A, and a second unit, B, is centered over the aperture, 5, of the cover. Using the plunger, 3, the tissue petal units, A and B, are pushed gently through the apertures to the extent indicated in Figure 2; the plunger, 3, is then removed, and the apparatus is inverted to the position shown in Figure 3. The cover member, 2, thus supports the partially formed flower out of contact with the table surface, and the centrally gathered portions, A¹ and B¹, of the petal units are presented upwardly, as seen in Figure 3. A loop of wire, C, is gathered about the calyx, A¹, B¹, and the ends, C¹, of the wire may be twisted together and disposed substantially along the axis of the blossom. The box cover, 2, is then withdrawn over the petal member, B, temporarily gathering the petals quite closely, and the box member, 1, may be withdrawn in the same direction, if desired, or since the aperture, 4, therein is smaller than the aperture, 5, it may be removed in the opposite direction over the stem. The calyx of the blossom and the stem formed of the wire are then wrapped with any suitable material, such as a strip of green crepe paper, D, as seen in Figure 4.

Figures 5, 6 and 7 illustrate a modification of the apparatus in which the box cover, 2, is replaced by an annular member shown as a ring, 6, having a central opening slightly larger than the aperture, 4. It may be of any suitable material, such as celluloid, and of substantial thickness sufficient to separate the petal units A and B during the forming process so as to allow the petals formed by each unit to take shape independently of the other unit. Figure 6 illustrates the step of forcing the central areas of the disks, A and B, through the aperture, 4, in the box member, 1, with the ring, 6, interposed between the disks, A and B. Figure 7 shows how the box member, 4, may be set up so as to rest on one of its lateral flanges, 1^a, to avoid crushing the partially formed petals while at the same time presenting the calyx composed of

their central portions, A¹ and B¹, in position for application of the wire loop, C. The remainder of the process is similar to that already described, it being understood that the ring, 6, 5 may be slipped off from the petal unit, B, causing the petals to be temporarily gathered, and then permitting them to expand into their final form.

It may be understood that artificial flowers of 10 various types may be made by this process, and that more than two petal units may be employed to produce a larger or fuller blossom. Figure 8 illustrates the use of three such units, A, B and E, respectively, in an apparatus employing the 15 box, 1, and its cover, 2, in the same manner as Figure 1, but with a third element shown as a flat annular disk, 7, which performs the same function as the ring, 6, of Figure 5, and is interchangeable therewith for separating the petal 20 units during their formation. The central aperture of the member, 7, is preferably of the same size as the aperture, 5, of the cover member, 2.

It may be understood that in the combination 25 of elements shown in Figure 5, a disk, 7, may be substituted for the ring, 6, and that, if desired, two or more such disks may be employed, or two or more rings, 6, may be employed with a corresponding number of petal units to form a flower; and, likewise, in an arrangement such 30 as that shown in Figure 8, a ring, 6, or a plurality of rings with a suitable number of petal units may be substituted for the ring, 7, as shown.

It may also be understood that since the cover 35 member, 2, is slightly larger than the box, 1, and is telescopically related thereto, it may be applied over the inverted box with its flange portions, 2^a, extending down over the flanges, 1^a, and with the petal member, A, interposed; this 40 arrangement ensures centering of the aperture, 5, with respect to the opening, 4, but when the parts are thus employed the assembly will be set up on one of its flanged edges somewhat as shown in Figure 7 for applying the wire stem, C.

One special advantage of using either one or 45 both of the box elements in the process of forming the flowers is that the petal units are customarily sold in packs or piles, and can be most satisfactorily packaged in a box of this character along with the auxiliary rings or disks and the wooden plunger, which complete the apparatus. The package may also contain a small 50 quantity of wire and wrapping material for making up the stems. These materials are of such shape that there is no danger that they will escape through the aperture 4 or 5 in the box and its cover, but in most cases a paper circular of directions or the package of tissue petal disks will be placed immediately adjacent the apertured wall to ensure retention of the contents of the package. The utilization of the box elements as functioning parts in the formation 55 of the flowers simplifies the apparatus as to the number of parts, and since the box is of standard construction it requires no special machinery or process for its manufacture beyond the punching of the central apertures in its bottom wall and cover.

While there is shown and described herein certain specific structure embodying the invention, it will be manifest to those skilled in the art that various modifications and re-arrangements of the parts may be made without departing from the spirit and the scope of the invention, and that the same is not limited to the particular form herein shown and described, except in so far as indicated by the appended claims.

I claim:

1. An apparatus, for containing and folding into flower-form petal elements of an artificial flower, comprising a box member consisting of a diaphragm wall and a peripheral flange projecting at one side only of the diaphragm wall, a 15 cooperating box member engageable with said flange for closing the box cavity, the diaphragm having a relatively small central aperture, a substantially flat member having also a central aperture adapted to register with the box dia- 20 phragm aperture when the flat member is applied to the outer side of the diaphragm with the box member resting on its flange, and a thrust rod dimensioned for thrust through the registered apertures with clearance for accommodating the 25 thickness of the petal elements which are to be folded through said apertures.

2. A container for petal elements of artificial flowers adapted to serve as a tool for assembling 30 said petal elements in flower form, said container consisting of a box and telescoping cover therefor each comprising a flat diaphragm and a completely continuous peripheral flange projecting from one side only of the diaphragm, said diaphragm and cover having each a relatively 35 small aperture, said apertures being respectively positioned for registering with each other when the box and cover are inverted and upheld one upon the other, diaphragm to diaphragm, for co-operation of said diaphragms with each other, 40 and with petal element or elements lodged above said diaphragms respectively for flower formation, said apertures being adapted to admit a plunger of suitable dimensions through them for flexing the petal elements therethrough. 45

3. An apparatus for assembling and folding into flower form petal elements of an artificial flower comprising a box consisting of diaphragm bottom and peripheral flange projecting at one side only of the diaphragm bottom, and a cover 50 cooperating with said flange for closing the box cavity, the diaphragm having a relatively small substantially central aperture, the cover member having a similar aperture positioned for registering with the box diaphragm aperture when the cover is applied to the outer side of the diaphragm of the box at inverted position, and a thrust rod dimensioned for thrust through the 55 apertures of the box diaphragm and cover with clearance for accommodating the thickness of the 60 petal elements which are to be folded through the diaphragm aperture.

4. The construction defined in claim 2, the aperture of the cover member being slightly larger than the aperture of the diaphragm of the 65 box member.

ROBERT N. BURTON.
